[57] CLAIM

The ornamental design for a combined wrist and hand support, as shown and described.

DESCRIPTION

FIG. 1 is a front elevational view of the preferred embodiment of a combined wrist and hand support;

FIG. 2 is a top plan view of the design of a combined wrist and hand support shown in FIG. 1;

FIG. 3 is a bottom plan view of the design of a combined wrist and hand support shown in FIG. 1;
FIG. 4 is a rear elevational view of the design of a combined wrist and hand support shown in FIG. 1;
FIG. 5 is a right side elevational view of the design of a combined wrist and hand support shown in FIG. 1;
FIG. 6 is a left side elevational view of the design of a combined wrist and hand support shown in FIG. 1;
FIG. 7 is a partially fragmented front elevational view of the design of a combined wrist and hand support shown in FIG. 1;

FIG. 8 is a front elevational view of an alternate embodiment of a combined wrist and hand support;

FIG. 9 is a top plan view of the alternate embodiment shown in FIG. 8 of a combined wrist and hand support;
FIG. 10 is a right side elevational view of the alternate embodiment shown in FIG. 8 of a combined wrist and hand support;

FIG. 11 is a rear elevational view of the alternate embodiment shown in FIG. 8 of a combined wrist and hand support;

FIG. 12 is a bottom plan view of the alternate embodiment shown in FIG. 8 of a combined wrist and hand support;

FIG. 13 is a left side elevational view of the alternate embodiment shown in FIG. 8 of a combined wrist and hand support; and,

FIG. 14 is a partially fragmented front elevational view of the alternate embodiment shown in FIG. 8 of a combined wrist and hand support.
